[57] CLAIM

The ornamental design for a simulative driving toy, as
shown and described.

DESCRIPTION

FIG. 1 is a top perspective view of a simulative driving
toy showing my new design;
FIG. 2 is a left side elevational view thereof;
FIG. 3 is a front elevational view thereof;
FIG. 4 is a bottom plan view thereof;
FIG. 5 is a rear elevational view thereof; and
FIG. 6 is a right side elevational view thereof.
